Patented Apr. 11, 1922.

Inventor

Ernest Henry Ruediger,

By Hiram A. Sturges,
Attorney

UNITED STATES PATENT OFFICE.

ERNEST HENRY RUEDIGER, OF BISMARCK, NORTH DAKOTA.

COMBINED COLD-WATER BATH AND REFRIGERATOR.

1,412,198.

Specification of Letters Patent. Patented Apr. 11, 1922.

Application filed January 30, 1922. Serial No. 532,527.

To all whom it may concern:

Be it known that I, ERNEST HENRY RUEDIGER, a citizen of the United States, residing at Bismarck, in the county of Burleigh and 5 State of North Dakota, have invented certain new and useful Improvements in a Combined Cold-Water Bath and Refrigerator, of which the following is a specification.

This invention has for its object, broadly, 10 to provide a container having two storage compartments with temperatures modified in different degrees by use of ice and water in an ice chamber and flowing ice water therefrom, one of the storage compartments having 15 a perforated bottom for a communication with the ice chamber to permit ice water to enter so that its temperature may be only slightly greater than 32 degrees F., and having a discharge element between its top and 20 bottom and lower than the top of the ice chamber to permit drainage, so that ice water will automatically flow therethrough to maintain the temperature approximately uniform in degree. One of the specific objects 25 of the invention is to provide an article particularly adapted for household uses, consisting of few parts which may be conveniently and economically manufactured.

The invention consists of the novel construction, combination and arrangement of parts as described herein and claimed, and as illustrated in the accompanying drawing, 30 wherein,

Fig. 1 is a view in longitudinal section of a 35 combined cold water bath and refrigerator, embodying my invention. Fig. 2 is a view in transverse section, and Fig. 3 is a front view of the same.

Referring now to the drawing for a more 40 particular description, numeral 4 indicates an upright housing or container, similar to the walls of refrigerators in general use, the lid therefor being indicated at 5.

Numeral 6 indicates an ice chamber, open 45 at its top, its walls preferably being constructed of metal; and at 7 is indicated a storage compartment, open at its top and communicating with the chamber 6 by means of numerous apertures 8 formed in its bottom 9. Numeral 10 indicates a wall having 50 a height less than the height of the partition *a* which separates the compartment 7 from said chamber 6.

At 11 is indicated a drain-pipe communicating with the compartment 7, and at 12 is

indicated a storage compartment which is disposed below the ice chamber.

In operation, after the chamber 6 is filled with ice, water is added and, obviously, will enter the storage compartment 7 by passing through apertures 8, the quantity of water thus added being sufficient to fill said compartment 7 to a depth equal to the height of the wall 10, and water coming thereafter from melted ice will flow through apertures 8 and storage compartment 7 to pass to the drainage pipe, the top *b* of the wall 10 being lower than the top of the partition *a* adjacent to which ice is stored, the top *b* of said wall 10 defining the intake for the drain 70 pipe 11.

On account of the construction as described, the temperature of the water in the storage compartment 7 will be nearly as low as 32 degrees F., which, obviously, is a great 75 advantage as compared with air cooled in the presence of ice. While the temperature in the storage compartment 12 will not be as low as provided for the compartment 7, it is considered that the movement of ice water 80 closely adjacent thereto will operate to advantage in maintaining said compartment 12 at a lower degree of temperature than ordinary.

While I have shown and described details 85 of construction, I do not wish to be understood as limiting myself in this respect, and changes in size, form, proportion and minor details may be made as found to be of advantage, said changes being determined by 90 the scope of the invention as claimed.

It will be noted that the ice chamber 6 is approximately of L-shape in side elevation, and that the ice-water compartment 7 is disposed above the horizontal extension of said 95 L-shaped chamber, the perforated top of said horizontal extension forming the bottom of the compartment 7; and on account of the arrangement of parts as described, ice and moving water will modify the temperature 100 to advantage.

I claim as my invention:

1. In a cold water bath and refrigerator, an upright housing provided with a plurality of vertical and horizontal partitions defining a chamber for containing ice and water and a second chamber having an upright imperforate wall terminating in a plane lower than the top of the first named chamber, permitting a discharge of water 110

over the top of said wall, and having a perforated bottom located above and directly over the bottom of the ice and water chamber, and below the top thereof, whereby
5 water of substantially the same temperature as the ice may enter said second chamber.
2. In a combined cold water bath and refrigerator, an upright housing provided with
10 a plurality of vertical and horizontal partitions defining a chamber approximately of
L-shape in side elevation for containing ice and water and a second chamber below and
15 adjoining the L-shaped chamber, a drain-pipe, that part of the top of the horizontal
extension of said L-shaped chamber having

an upright imperforate wall terminating in a plane lower than the top of said L-shaped chamber defining a third chamber for containing ice water, the bottom of said third chamber being perforated to permit a movement of water from the L-shaped chamber to the drain-pipe by passing through the third chamber. 20

In testimony whereof, I have affixed my signature in presence of two witnesses.

ERNEST HENRY RUEDIGER.

Witnesses:

L. A. SCHIPFER,
B. H. SCHNEIDER.
